Primary Examiner — Barbara Fox*Assistant Examiner* — Aram Kwon(74) *Attorney, Agent, or Firm* — Birch, Stewart, Kolasch & Birch, LLP(57) **CLAIM**

The ornamental design for a television set, as shown and described.

DESCRIPTION

FIG. 1 is a front, right perspective view of the television set showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is an enlarged view of the enclosed portion 8 as illustrated in FIG. 1; and,

FIG. 9 is an enlarged view of the enclosed portion 9 as illustrated in FIG. 4.

The dot-dot-dash broken line showing in FIGS. 1, 4, 8 and 9 is for the purpose of illustrating partially enlarged views and forms no part of the claimed design.

1 Claim, 5 Drawing Sheets(56)
